(57) **CLAIM**
We claim the ornamental design for a device for killing insects with heat, as shown and described.

DESCRIPTION

FIG. 1 is a first perspective view of a first embodiment of a device for killing insects with heat;

FIG. 2 is a second perspective view of the first embodiment of a device for killing insects with heat;

FIG. 3 is a third perspective view of the first embodiment of a device for killing insects with heat; and

FIG. 4 is a bottom view of the first embodiment of a device for killing insects with heat.

FIG. 5 is a first perspective view of a second embodiment of a device for killing insects with heat;

FIG. 6 is a second perspective view of the second embodiment of a device for killing insects with heat;

FIG. 7 is a third perspective view of the second embodiment of a device for killing insects with heat; and

FIG. 8 is a bottom view of the second embodiment of a device for killing insects with heat.

FIG. 9 is a first perspective view of a third embodiment of a device for killing insects with heat;

FIG. 10 is a second perspective view of a third embodiment of a device for killing insects with heat; and

FIG. 11 is a top view of a third embodiment of a device for killing insects with heat.

FIG. 12 is a first perspective view of a fourth embodiment of a device for killing insects with heat; and,

FIG. 13 is a second perspective view of the fourth embodiment of a device for killing insects with heat.

The broken line showing of environment in the drawings is included for the purpose of illustrating only and forms no part of the claimed design.
